[57] CLAIM

The ornamental design for a temperature controlled medicine container, as shown and described.

DESCRIPTION

FIG. 1 is a perspective view of the temperature controlled medicine container showing my new design;
FIG. 2 is a front elevational view thereof;
FIG. 3 is a rear elevational view thereof;
FIG. 4 is a right side elevational view thereof, the opposite side being a mirror image;
FIG. 5 is a top plan view thereof; and,
FIG. 6 is a bottom view thereof.

FIG. 1.

FIG. 5.

FIG. 2.

FIG. 6.

FIG. 3.

FIG. 4.
